RAMON MARPONS CATÁ, OF BARCELONA, SPAIN

PENCIL WITH SLIDING LEAD

Application filed June 20, 1929; Serial No. 372,485, and in Germany October 27, 1928.

The present invention refers to pencils with sliding leads.

The common or customary pencils are composed of a stick of graphite, or of graphite and clay, and even of caolin, or other material which is not necessary to specify, the said stick being called "lead" and being enclosed in a cylindrical or prismatic covering, of wood, which protects it, and gives body to the pencil, thus making it convenient to use.

In order to uncover the lead of the pencil, or, as commonly said, to sharpen the pencil, it is necessary to cut away portions of the enclosing wood, with the object of allowing more or less of the end of the lead to project, and this portion must be sufficiently pointed to permit the lines traced by the pencil to be sufficiently fine.

This operation of sharpening a pencil, although simple requires some ability and a certain amount of skill, and in any case it is difficult to obtain perfect results.

For this reason a great number of instruments and machines have been evolved to automatically secure properly sharpened points, but up to the present time, not even the relatively high priced ones have given practical and completely satisfactory results, for various reasons, which are also unnecessary to analyze.

In view of the foregoing, the inventor, realizing how difficult it is to perfectly achieve the ready removal of the wood which is requisite in the above described operation, has conceived the idea of producing pencils made in such a way that enough of the lead may be exposed without any need to remove any part of the surrounding wood which constitutes the outer covering of the pencil.

In order to achieve this, the lead, instead of firmly adhering to the surrounding material as at present, is a body independent of the said material, and it lies in it in such a way, that it can be made to slide through the interior in a longitudinal direction, on being given a slight push. The covering should preferably have, in that part where the end of the lead is to come out, a form converging towards the center; for example a conical

Each time it is necessary to renew the point of the pencil all that will be needed, is to slightly push the lead at the end opposite to the pointed portion, by means of a wire or rod which is introduced as far as necessary 55 into the channel or groove in which the lead is placed.

To complete the operation of sharpening the pencil, it will only be necessary to sharpen the lead, which can be easily done with a rasping instrument, and there will be no need to cut away any wood at all, a perfect point being obtainable without this.

In the attached drawings is shown by way of example a pencil arranged in accordance 65 with the object of the invention showing:

Fig. 1, a vertical section of a pencil with shiftable lead and means of holding the lead.

Fig. 2, a cross section on a line perpendicular to the Fig. 1, the holding device for 70 the inner end of the lead being shown in elevation.

Fig. 3, a perspective view of the holding device of the inner end of the lead.

Fig. 4, a vertical section of the protecting 75 tube showing the push rod in elevation and a device for sharpening the lead of the pencil.

Fig. 5, a cross section of the spring that holds and supports the supplementary rod.

The details of the drawings are as follows:

1 body of the pencil, 2 bore in the body 1, 3 the lead, 4 holding device for the lead, 4a-4b arms of the spring, 5-5' pivots which make the spring bear against the walls of 85 the bore, 6 point of the pencil, 7 additional cap, 8 grooves in the cap, 9 push rod, 10 protecting tube, 11 support of the additional rod, 12 additional rod, 13 holding spring for the same, 14 sharpener, 15 holding screw for 90 the sleeve 16, 17 wall dividing the sharpener from the rest of the support.

In the drawing may be seen the protecting cover made of wood which has a groove or channel at 2, in which is placed the lead 3 95 which can slide along said channel 2.

The end of the cover 1 has a conical form, and at the vertex of the same emerges the point of the lead 2.

Behind the lead 3 a device 4 is arranged 100

consisting of an elastic clamping spring with two pivots 5—5' holding it elastically in its place.

This spring presses on the end of the lead in such a way that it cannot turn round or move back or sideways.

For greater convenience, and to avoid the conical end of the envelope of the lead getting dirty with use, in view of the fact that in the 10 case of this kind of pencil the wood must not be cut in order to give it a more aesthetic appearance, at the conical end of the pencil a device 7 can be provided, which presses on the point at its sides 8—8'.

15 To make the lead advance through the bore as it is worn, a device has been provided which is composed of a protecting tube 10 which has a push rod 9 fixed in its centre. Further an additional rod 12 has been provided, held in the interior of the protecting tube 10 in the base 11 by means of the holding spring 13.

To make the lead go down through the bore the rod 9 is utilized, fixed in the protecting tube. This way of pushing down the lead is of the greatest importance, for it ensures the maximum convenience and security.

All that need be done is to place the pencil in the protecting tube 10, and then the rod 30 9 is automatically introduced into the bore 12, when it will act on the lead through the pressure that can be exerted with the hand. In this way any person, even a child can make the lead of the pencil move with the greatest

35 facility. In all the other systems the contrary takes place, even those that have been conceived but which no one has put in execution, due, no doubt, to the difficulty of pushing the lead down with a wire rod or other similar object, for apart from the difficulty in finding the centre of the lead, due to the pressure it would be necessary to exert, the rod would bend and easily cause injuries to the hand. This system would also be open to the 40 objection that it would be very inconvenient to carry, especially for school children.

When the rod 9 no longer reaches the lead, the additional rod 12 is introduced, this rod being held by the spring grip 13 in the interior of the protecting tube 10 in the bore of the pencil, and thus the fixed rod 9 protected in the tube 10 will push the additional rod 12, and the lead can be made to emerge to the extent necessary every time this is 45 required, until it comes to an end.

Finally a means has been provided for sharpening the lead as required.

With this object there is at the end of the 50 additional rod 12 opposite to the support 11, a sharpener 14. This sharpener can be formed in different ways, and may be constructed as a cone, made of carborundum or other rasping material 14, which also carries a holding screw for the blade and the 55 blade 16.

Another form of construction would be, for example, a cone formed by a series of strips whose cutting edges touch the lead of the pencil and sharpen it by simple friction.

70 In the attached drawing yet another form of execution is shown of the sharpener (Fig. 6). In this drawing will be seen a cone 14 made in one piece of metal or other appropriate material. In the interior of the cone 75 there is a blade 16 held by a screw 15. In the angle of inclination given to the blade 16 in relation to the other view of the cone a means is provided for giving the required degree of sharpness to the lead.

80 In the form of execution shown in the drawing there are included in the same apparatus the protecting tube 10, the push rod 9, and the additional rod 12, with the sharpener 14, and this constitutes an enormous 85 advantage which ensures that the operations of pushing the lead through the bore and sharpening it be carried out by the simplest means, and this with an apparatus of the smallest size.

90 Meanwhile the actual manufacture of lead pencils consists in the formation of two half circles of wood or other suitable material which are glued and after putting the lead between them pressed together solidly. The manufacture of the pencils with sliding leads and especially with very thin lead 95 would be preferably performed otherwise.

99 The mode of manufacture would consist in forming also the two half circles and to 100 join them by suitable means but instead of putting the lead in the channel so formed, there would be rods or wires, of the same diameter as the lead had to be placed between those two halves. After they have 105 been fitted together perfectly well, the rod or wire is extracted and the lead introduced through the end part with great ease. The leads so introduced will have exactly the 110 size needed and during the writing they will not move in any direction, but remain in their place.

115 What I claim is:—

A pencil with shiftable lead flattened on the inner end, comprising in combination a hollow body of the pencil, a metal clip having two arms adapted to grip around the inner end of the lead guided in said hollow body and a locking element on each of said arms adapted to prevent the lead from sliding back into said body when the pencil is 120 being used.

125 In testimony whereof I affix my signature.

RAMON MARPONS CATÁ.
